UNITED STATES PATENT OFFICE.

THOMPSON HARRIS LYON, OF RENFREW, PENNSYLVANIA.

WAVE-DETECTOR.

1,008,977.

Specification of Letters Patent. Patented Nov. 14, 1911.

Application filed October 12, 1911. Serial No. 654,257.

To all whom it may concern:

Be it known that I, THOMPSON HARRIS LYON, a citizen of the United States, and a resident of Renfrew, in the county of Butler and State of Pennsylvania, have invented a new and Improved Wave-Detector, of which the following is a full, clear, and exact description.

My invention relates to wave detectors, and more particularly to wave detectors of the kind known as rectifiers and which employ crystalline or crystalloid substances to be energized by electric oscillations and which may be employed in connection with wave meters as well as in the commercial and experimental sending of messages in wireless telephony and telegraphy.

My improved wave detector, because of its character as a rectifier, does not necessarily require a battery or other source of local current, as is the case with many kinds of wave detectors.

The wave detectors of the rectifier type heretofore produced usually lose much of their sensitiveness after being in use for some time, and particularly if strong electric currents are passed through them, or if they are employed in close proximity to a powerful radiating circuit. Such detectors need frequent adjustment and in many instances are troublesome to adjust properly.

The purpose of my invention is to provide a wave detector of the rectifier type which, while simple in construction, is comparatively sensitive, does not deteriorate in use, is affected very little by local disturbances, needs only occasional adjustment, and can be easily and quickly adjusted whenever necessary.

I have made the discovery that the lead ore known as cerusite ($PbCO_3$) has such natural properties as are fitted for use in carrying out the objects just stated. No particular form of mounting is essential to the use of this material in the relation stated, but for convenience I show a very simple form of mounting for this purpose.

Reference is made to the accompanying drawing forming a part of this specification, in which like characters of references indicate corresponding parts in the view, and in which the figure shows a vertical section through my improved wave detector.

Mounted upon a base 1 are two posts 2, 3, and connected with the latter are wires 4, 55 5 which may be connected in the conventional or any desired manner at a wireless receiving station. The post 2 is provided with a slot 6 in which is clamped a fragment 7 of cerusite ore. The post 3 is provided with a slot 9, and adjustably mounted within the latter is a holder 10 carrying a small wire electrode 11 made, in this instance, of platinum, and whose end is in contact with the fragment 7 of cerusite ore. By 60 adjusting the holder 10, the pressure of the electrode 11 upon the fragment of ore may be adjusted with any degree of delicacy desired. The position of the electrode point upon the ore may also be shifted or adjusted 65 by shifting the position of the holder 10 with any degree of delicacy desired. The manner of mounting the fragment 7 is not materially different from that of mounting other fragments of crystalline or crystalloid 70 substances, and the mounting and adjustment of the electrode 11 will be readily understood from analogies found in this art. The cerusite ore being of a metallic nature has a relatively low resistance, and consequently any ordinary telephone receiver may 75 be used in connection with it.

I do not limit myself to any particular apparatus for holding the fragment 7, or to any precise means of adjusting the electrode 80 11, or to any precise kind of electrode for engaging the fragment 7, my invention relating to the substance employed because of the effect that electric oscillations have 85 upon it.

Having thus described my invention, what I claim as new and desire to secure by Letters Patent is:—

As an element of a means for receiving intelligence communicated by electro-magnetic waves, the substance cerusite, substantially as and for the purpose described.

In testimony whereof I have signed my name to this specification in the presence of two subscribing witnesses.

THOMPSON HARRIS LYON.
